GRINDING MILL

Leonard Dotzer, Milton, Mass.

Application May 28, 1941, Serial No. 395,591

5 Claims. (Cl. 83—?)

This invention relates to improvements in reducing and grinding mills of those types and for the purposes, of the mills disclosed in U. S. Letters Patent No. 2,176,892, issued to Leonard Dotzer et al. on October 24, 1939, and also of those mills disclosed in my pending application, filed August 19, 1939, under Serial No. 291,026. Both in the pending application and in the patent, various mills have been shown and described, wherein three coaxially aligned grinding stones are employed in face to face relationship, thus providing that material may be ground, or reduced, between the coacting surfaces of the opposite surfaces of the central stone and inner surfaces of the stones at opposite sides of the central stone.

More particularly, the present invention relates to improvements in mills of the above stated kind, designed for the initial crushing of cocoa nibs and the subsequent fine grinding of the particles.

The objects of the present invention are mainly concerned with the provision, in mills of the above character, of hydraulic means for equalizing and regulating the grinding pressures, as applied by the stones at upper and lower sides of the middle stone against the middle stone.

Explanatory to the present invention, it will here be stated that in those mills featured in my above mentioned pending application, employing three, coaxially arranged stones and providing for the grinding of material at both sides of the central stone, the central stone is designated as being of the floating type; that is, it does not have fixed mounting with respect to its vertical movement, but adjusts itself automatically between the top and bottom stones in accordance with the applied grinding pressures, and the pressure of springs which are employed to act against the stones to effect a yielding application of the grinding pressures.

In such an arrangement of stones and pressure applying springs, it is a difficult matter to establish and then to maintain any definite grinding pressure for an extended grinding period or to maintain equalized grinding pressures on opposite sides of the middle stone. This is due partly to the manner of mounting the stones and influences of the weight of the various stones, as well as to the fact that the tension of the pressure applying springs will vary or change with use and with their change in temper. Thus, to maintain equality in grinding pressures at opposite sides of the middle stone, it is required that special precautions be taken, that frequent tests be made, that spring pressures must be accurately measured and adjustments made accordingly.

Furthermore, unequal pressures at upper and lower sides of the middle stone that result from the influences of weight of the stones, requires that a lesser feed of material must be applied to

the grinding space at the top surface of the middle stone than to the lower surface. This naturally results in a loss of grinding efficiency in the mill.

5 In view of the above difficulty, and for other reasons which will later become apparent, it has been the principal object of this invention to provide a mill construction employing three horizontal, axially arranged stones, and wherein 10 equalized grinding pressures at upper and lower sides of the intermediate or the central stone can be obtained in a satisfactory and practical manner by economical and inexpensive means to bring about a higher operating efficiency in the mill, due to the fact that material to be ground may be fed to both sides of the middle stone in equal amounts and ground at the same pressures.

It is a further object of the present invention to provide novel means for effecting an equalization of pressure, embodying hydraulic jacks that are arranged to act against the upper and lower stones in a manner whereby to urge them toward the middle stone at pressures that will either compensate for or not be influenced by the effect of the weights of the stones.

It is a still further object of this invention to provide a grinding mill of the character above stated, using three horizontal, coaxial stones, and wherein the central stone is rotatable but is held against vertical movement during operation, providing that the opposing pressure, applied by the grinding stone, whether at the top or at the bottom side thereof, will not alter or affect the grinding pressure applied by the stone at the opposite side.

Another object of this invention is to provide novel devices whereby the upper stone, when not in use, may be held suspended and in spaced relationship from the middle stone, and manually or automatically controlled means whereby these suspending devices may be simultaneously released from the stone for its functional operation.

45 Another object of the invention is to provide a mill using segmental stones and a practical means for bringing the segments of any stone to a common level.

Still further objects of the invention reside in 50 the details of construction of parts, in their combination and in their mode of operation, as will hereinafter be fully described.

In accomplishing these and other objects of the invention, I have provided the improved details of construction, the preferred forms of which are illustrated in the accompanying drawings, wherein—

Fig. 1 is a vertical, sectional view of a mill embodying the present invention, as seen in the 55 vertical, axial plane of the grinding stones.

Fig. 2 is a top or plan view of the same; a part being broken away for better illustration.

Fig. 3 is a horizontal section on the line 3—3 in Fig. 1, particularly illustrating the base frame structure.

Fig. 4 is a horizontal section, taken on line 4—4 in Fig. 1, particularly showing the supporting frame for the upper grinding element.

Fig. 5 is an enlarged sectional detail taken on the vertical plane of line 5—5 in Fig. 4.

Fig. 6 is an enlarged sectional detail taken on line 6—6 in Fig. 8, illustrating the means for adjusting and securing one of the stone segments in place in its frame.

Fig. 7 is an outer edge view of the stone, showing the securing plates.

Fig. 8 is a plan view of the central grinding element.

Fig. 8a is a sectional detail of one of the breaker plates.

Fig. 9 is a vertical sectional view showing the relationship of grinding elements in the machine.

Fig. 10 is a cross sectional detail of the wheel structure as seen on line 10—10 in Fig. 8.

Fig. 11 is a view diagrammatically illustrating a hydraulic system for the pressure applying and supporting jacks for the upper and lower grinding elements.

Fig. 12 diagrammatically shows a hydraulic system for a mill having a floating center stone.

Briefly described, the present mill comprises a frame structure wherein three horizontally disposed grinding elements, or stones, are arranged in coaxial alinement; the central element is rotatably mounted and is driven by a gear pinion meshing with a ring gear which encircles and is fixed to the element. The upper and lower elements are held against rotation and are adjustably spaced from the upper and lower surfaces of the central element. Conventional means is provided for feeding the material to be ground between the opposed grinding surfaces of adjacent elements, and means, according to this invention, is provided for regulating the grinding pressures applied through the mediacy of the stones. Ground material is centrifugally discharged from between the coacting surfaces of the grinding elements to a receiving trough and is delivered from the machine.

Referring more in detail to the drawings—

In its present illustrated form of construction the present machine comprises a base frame structure which, as noted best in Figs. 1 and 3, includes a central horizontally disposed metal ring 1 and a larger, outer ring 2; this latter ring being formed from an angle bar and being disposed concentrically of the ring 1. The two rings, 1 and 2, are supported substantially at the same horizontal level through the mediacy of three vertical frame structures constituting the supporting legs of the machine, and these legs are equally spaced about the rings at intervals of 120°; each leg frame comprising inner and outer upright channel members 3 and 4, joined across their upper end portions by horizontal bars, as designated at 5. The lower ends of the outer channel members 4 are fixed to an encircling ring 6 that is disposed flatly upon and secured to a bottom or bed plate 8. The upper end portions of the channel members 3 and 4 of each leg frame are fixed, by welding or otherwise, respectively to the central ring 1 and to the ring 2.

The frame structure of the machine also in-

cludes an upper, or top section, as shown best in Fig. 2. This comprises a horizontally disposed central ring 10 about which a triangular, horizontal frame is symmetrically disposed; this frame comprising the three channel beams 11 joined at their ends by blocks 12 and supported from the ring 10 by interposed web plates 13. The beams 11 are joined and braced across the angles by vertical, spaced plates 14—14', thus with the beams 11, providing a rigid, three sided frame section.

This upper frame section, as presently will be understood, mounts the hydraulic jacks whereby the grinding pressure of the upper stone is regulated.

The upper section of the frame structure is supported rigidly from and in spaced relationship above the base frame structure, by three vertical columns or posts 15. These posts are fixed at their lower ends in bearing blocks or brackets 16 that are secured to the outside of the base frame at the location of the supporting legs. At their upper ends, the posts likewise are fixed in bearings formed by the blocks 12 and caps 12a that are applied and bolted to the blocks over the post ends. These three posts are shouldered near their ends to seat firmly against the faces of the bearings. Nuts, as at 17, are threaded onto the ends of the posts to rigidly secure the parts.

Fixedly supported within the central ring 10 of the upper frame section, is a three-armed spider 20, and likewise rigidly supported within the central ring 1 of the base frame section, is a similar spider 21. Mounted by these two spiders at the axial center of the machine, is a vertical shaft 22 which is the supporting axis for the central grinding element presently to be disclosed. The upper end portion of the shaft 22 is revolvably mounted in a bearing 23 at the center of the spider 20 and the lower end portion is contained in and is supported by anti-friction, double thrust bearings as at 24 contained in a housing 25 formed at the center of the spider 21. A downwardly facing shoulder 26 formed about the lower end portion of the shaft 22, engages against the top bearing 24 to support the shaft against downward movement.

Fixedly mounted on the vertical shaft 22 is the central grinding element of the mill which, for convenience, as considered in its entirety, will hereinafter be referred to as the central grinding wheel. This wheel comprises a metal frame structure which mounts breaker plates and grinding stones on its upper and lower faces, as later will be more fully described.

The wheel frame is formed with an elongated, central hub bearing 27 which is bored to receive the shaft 22. About the central bore is an annular passage 28 divided, as noted in Fig. 8, by a plurality of vertical webs 29 forming a plurality of openings that extend vertically through the hub for the feeding of material that is to be ground, to the lower side of the wheel, as presently will be explained. Spokes 29 extend radially from the wheel hub and at their outer ends mount a ring 30 formed with an encircling band of gear teeth 31 for driving the wheel; it being understood that the wheel is coaxial of shaft 22 and that the wheel hub 27 is so fixed or keyed on shaft 22 that no vertical movement of the wheel is possible under application of

grinding pressures either at top and bottom sides thereof.

Mounted centrally upon the frame structure of the central grinding wheel is a flat, annular breaker plate or disk 34. This has a diameter approximately half that of the wheel and has a central opening. The peripheral portion of the disk 34, about this central opening, rests upon and is fixed to an annular shoulder 27' formed about the upper end portion of the hub 27 of the wheel, and this central opening conforms in diameter to that of the annular passage 28, and thus it does not interfere with feeding of material to or the downflow of material through the annular passage. About its outer periphery, the breaker plate 34 rests upon and is secured to a ring 35 that is mounted on the radial arms, or spokes 29, of the wheel.

Supported by the spokes 29 of the wheel, about the breaker plate, is an annular floor plate 33 surrounded by an upstanding ring 36 also fixed to the wheel. Mounted upon the plate 33 and confined between the rings 35 and 36 are the segments of a grinding stone 37 which forms the top grinding surface of the central wheel, and it will be observed, by reference to Fig. 1, that the diameter of this stone, which is concentric of the wheel, is such as to leave an annular space 38 between the ring gear flange and the outer periphery of the stone for a downflow of ground material, or chocolate liquor, as it is exuded from between the coacting surfaces of the top and central stones.

It will here be explained that the coacting breaker plates of opposing elements as used in the present machine, are not primarily for grinding purposes, but rather are for the crushing or breaking up of the cocoa nibs into pieces of proper size for their passage between the coacting surfaces of opposed grinding stones for a finer reduction.

To best accomplish its purpose, the grinding surface of each breaker plate is formed with alternating ridges and grooves which may be patterned according to the showing in Fig. 8, wherein the plate is divided into segmental sections of equal extent and the ridges and grooves as applied over the area of each segment are parallel and lead toward the periphery of the disk for centrifugal delivery of crushed material. It will be further understood that the patterned surfaces of opposed breaker plates, due to rotation of the center wheel, operate on the material that is fed between them, to crush and then advance the crushed material to the surrounding grinding stones.

In Fig. 8a, I have shown an enlarged cross sectional view of the grooved surface of a breaker plate wherein the grooves are designated by reference numeral 39 and the ridges by numeral 39'. The walls of the ridges and grooves are evenly rounded to facilitate the crushing operation without clogging. These plates are of cast steel or cast iron with their patterned surfaces chilled to great hardness. To secure the breaker plate 34 in place, it is tapped about its inner and outer peripheries and anchor screws 40 extend therethrough and into the hub and ring 35, as noted in Figs. 8 and 9.

The stone 37 is divided into a plurality of segments and these segmental portions 37a are set in cement on the top side of the center wheel, on plate 33 between the rings 35 and 36, and are adjusted and secured in place by means

shown best in Figs. 6, 7 and 8, wherein it is noted that for each stone segment, four leveling screws 42 are threaded upwardly through the metal floor plate 33 to supportingly engage with the segment; these screws being adjustable for the purpose of leveling the individual segments and to bring them all to a common level and their top surfaces substantially flush with the top surface of the breaker plate 34 prior to the setting of the cement. These adjusting screws are headed at their lower ends and their upper ends engage the stones at locations within what may be considered their corner areas, in order to provide firm bearing for the segments. After the stones have been properly leveled in the wet cement, they are left still until the cement has set, then the screws are pulled back to be free of contact with the stones as a precaution against their breaking the stones.

It is also to be observed that each segment 37a of the stone is held in place by three anchors 45 that are attached to the floor plate 33 and which extend upwardly and have flanges 45' turned inwardly at their upper ends to project into laterally opening sockets 46 provided in the inner and outer side surfaces of the stone segments, as will be understood best by reference to Figs. 6 and 7. It is to be noted that there are two spaced anchor plates 45 at the outside of each stone segment, securely welded to the floor plate 33, with their upper end portions 45' turned inwardly and cemented in the sockets 46 and that there is one, centrally located anchor at the inside of the segment. This latter anchor comprises a horizontal flange 45a cemented in the stone socket and mounted by a bolt shank 45b, see Figs. 6 and 8, applied within an inwardly opening notch 47 in the inner edge of plate 33. A nut 48 is applied to the lower end of the shank and is drawn tight after the cement has set.

In mounting these stone segments 37a, they are placed in position, brought to proper level by adjustment of the supporting screws 42, and then the spaces are cast out with cement, that is, they are grouted into place. The anchors are embedded in the cement at the same time while the inturned flanges of the anchors 45 are cemented in their respective sockets 46; it being understood that the sockets are oversize to more easily receive the inturned flanges and to provide that they might be completely embedded.

If any stone segment becomes cracked, or damaged, the anchor at the inside may be removed for release of the stone and this provides for removal of the stone segments for replacement.

The bottom side of the center wheel likewise mounts a downwardly facing breaker plate 34b and segmental grinding stone 37b like the corresponding parts at the top side of the wheel. These latter parts cooperate in the same manner with the corresponding parts of a bottom grinding stone, and for the same purpose as those at the top side of the wheel coat with the upper stone. Thus, in view of the description previously given of the breaker plate 34 and stone 37, as applied to the top side of the center wheel, it is not thought necessary that it be repeated with reference to the corresponding parts as applied to the bottom side of the wheel, and it will be understood that the foregoing description as it concerns the breaker plate 34 and stone segments 37, and their associated mounting means, applies equally to these parts, 34b and 37b, on the under side of the wheel. The breaker plate 34b is fixed to the lower end of wheel hub 27

and to a ring 35b corresponding to ring 35, while the several segments of the stone 37b are suspended from a floor plate 36b that corresponds to the upper floor plate 33.

To drive the center wheel, I have provided a vertical drive shaft 50, revolvably mounted in bearings 51 and 52 carried by frame brackets 53 and 54 secured to the upper and lower sections of the main frame. Keyed on this shaft 50 is a gear pinion 55, operating in mesh with the gear teeth of the center wheel, and near its lower end bearing, a pulley wheel 56 is keyed on the shaft about which a driving belt, as indicated at 57 in Fig. 3, may operate to drive the shaft 50 and thus rotate the center wheel. An electric motor, as at 58 in Figure 3, may be used to furnish power for operating the mill, or any other suitable driving means might be employed.

Now, describing the lower grinding stone and its mounting means: This, as noted in Fig. 1, comprises a vertically adjustable, but non-rotatable frame structure including a central, horizontally supported ring 60, from which three equally spaced radial arms 61 extend. At their outer ends, these arms mount guide bearings, or blocks 62 which are slidably fitted to the vertical post 15 to permit vertical adjustment of the frame while holding it against rotation.

Supported within the ring 60 is a spider frame 63 which includes a central hub portion 64 through which shaft 22 extends. This hub has an upwardly rounded top surface 65 spaced somewhat from the lower end of hub 27. Supported upon this spider hub 64 is an annular breaker plate 66 of the same kind or character as the breaker plates 34 and 34b previously described. The plate 66 is fixed to the spider 63, which, in turn, is fitted about its periphery for vertical adjustment in ring 60, and is held against rotation and for coaction with the breaker plate 34b on the bottom side of the center wheel.

The vertical adjustment provided for the spider 63 is in order that the breaker plate 66 may be adjusted toward or from the breaker plate 34b for finer or coarser initial breaking of the material that is to be ground. The peripheral ring 63' of the spider frame has threaded mounting upon three equally spaced adjusting screws 83 that are rotatably fixed in bosses 84 that are bolted or welded onto the inside of ring 60, as shown in Fig. 8. After an adjustment of the spider has been made, it may be secured by the tightening of set screws 83' that are threaded through the spider ring to holdingly engage the inner face of ring 60.

Supported upon the radial arms 61 of the frame structure for the lower grinding element, is a floor plate 67, and fixedly mounted on this, concentrically of the shaft 22, are spaced rings 68 and 69, forming a trough 70 between them. Also, the ring 60 is welded to plate 67 to fix them solidly together. The lower grinding stone 71 is also in segments and is located between the ring 60 and ring 63, and the individual segments are anchored to plate 67 in the same manner as was previously described with reference to the anchoring of the top stone to plate 33. These segments, like those of the top stone, are set in cement, as has been indicated. The top surfaces of the several segments of stone 71 lie flush with the top plane of the breaker plate 66.

The trough 70 which surrounds the lower stone and which is formed between the spaced rings 68 and 69, serves as a collector for the ground material exuded from between the grinding sur-

faces at upper and lower sides of the center wheel; the trough being concentric of the stones and fitted closely about the lower stone. A delivery chute 73 leads from the trough as noted in Fig. 1 at the left-hand side.

The frame structure provided for support of the upper grinding element comprises a central ring 74 from which three radial arms 75 extend. These arms mount guide bearing blocks 76 at their outer ends which are fitted slidably to the posts 15 for vertical adjustment of the frame while holding it against rotation. Encircling the ring 74 and mounted by the radial arms 75, is a base plate 77 from which the upper grinding stone 78 is suspended. This stone likewise may be made in segments, each segment to be secured in place by anchors as previously explained, and set in cement, or the like, to give greater solidity. The segments of stone 78 would be flush with the surface of a breaker plate or disk 80 that is mounted on the under side of a spider frame 81 slidably fitted for vertical adjustment within the ring 74, and is in opposed relationship to the breaker disk 34 of the central wheel.

The adjustment of the spider frame 81 for an adjustment of the breaker plate 80 toward or from the plate 34 is by means corresponding to those for the lower plate. Set screws 83a are rotatably fixed in bosses 84a bolted to the ring 74 and have threaded connection with the ring 81' that constitutes the base of the spider. Locking bolts 83' also are used to secure the spider at its different positions of adjustment. These extend through the ring 81' and may be tightened against the ring 74. The breaker disk 80 has a central opening 82 that is concentric of shaft 22 and somewhat greater in diameter than the opening in breaker disk 34.

It will be noted by reference to Fig. 1 that a cylindrical, upwardly extending sleeve 85 is mounted at its lower end upon disk 34 about the central opening. This sleeve extends upwardly slightly above the level of the top of ring 74, in Fig. 1, and is open to receive material from a feed pipe, that is to be ground between the coacting surfaces of the middle and bottom stone; this sleeve in effect is a continuation of the annular passage 28. Also, there is a similar sleeve 87 fitted at its lower end in the central opening of disk 80, and this also is adapted to receive material into its upper open end for delivery through the central opening of the disk 80. Feed devices have been designated at 88 and 88' in Fig. 1 with delivery spouts 89 and 89' leading to the upper ends of the two sleeves 85 and 87, and the flow of material therefrom to the grinding surfaces is as indicated by the arrows in Fig. 9.

Ground material will be exuded from between the grinding surfaces of the central and upper stones in the form of a thick paste and will fall into the annular space 38 just within the ring gear. A plurality of paddles, as at 91 are fixed to the stationary upper stone frame, which extend into the annular channel as a means of wiping the liquor from the periphery of the rotating central stone to cause it to drop through into the trough 70 that is directly below. Also, a plurality of similar paddles 91' are fixed to the center wheel to extend downwardly into the trough 70 to move the material therein to the discharge chute 73.

In order that the upper stone may, when left idle for some time, be held in suspension, spaced from the top side of the middle stone, I have provided three suspending hooks 94 pivoted in the

top frame, as noted in Fig. 1, and adapted to holdingly engage with cross pins 95 in the top stone supporting frame. Each hook has a lateral arm 96 operatively connected with a solenoid 97 in such manner that upon energizing the solenoids, all hooks will be simultaneously released from their pins and the stone will be allowed to lower. When the stone is lifted to a predetermined height, it causes the hooks to automatically engage their respective pins for suspension of the stone.

Assuming the parts to be so constructed and assembled, it will be understood that, with the central wheel rotatably driven and the upper and lower stones held against rotation, material that is fed between coating surfaces of the breaker plates and stones of the central and upper and lower stones will be crushed and ground. Furthermore, the extent of grinding will be in accordance with the feed and the degree of pressure of coating surfaces against the material.

As previously explained, it is desirable that these pressures at upper and lower sides of the central wheel be the same, and this is accomplished in the present instance by means that affords a desired pressure and at the same time compensates for the variances that are due to the weight of the upper stone which tends to increase its pressure and that of the lower stone which similarly tends to decrease its pressure.

The lower frame structure by which the lower breaker plate 66 and the stone 71 are carried is vertically movable and guided by the posts 15, and is adjustably supported through the mediacy of three single acting hydraulic jacks each designated by reference character 100. These jacks are supported vertically in the leg frames whereby the machine is supported. Each jack comprises a hydraulic cylinder 102 and a piston 103 from which a vertical rod 104 extends upwardly for supporting contact with the floor plate 67 within one of the radial arms 61 fixed to and extending from the ring 60 and constituting a part of the stone mounting frame. The arrangement provides that by extending and retracting the piston rods, the supporting frame structure for the lower stone will be raised and lowered accordingly.

Likewise, fixedly mounted by the upper frame structure carried by the upper ends of the shafts 15, are three double acting hydraulic jacks 110, each with a piston rod 111 extending downwardly and supportingly connected at its lower end with one of the radial arms of the upper stone mounting frame. The extent of application of hydraulic pressure medium to these sets of upper and lower jacks determines the grinding pressures at which the top and bottom stones are urged against or toward the central stone, and it can be understood that the weight of the top stone will ordinarily increase its pressure accordingly while weight of the lower stone will likewise decrease its effectiveness. Therefore, it is desirable that the pressure be controlled and that the effect of these weights be compensated for to such extent that the effective grinding pressures be equalized at upper and lower sides of the middle stone.

In Fig. 11, I have diagrammatically illustrated a hydraulic system for the present type of machine, having the middle stone held against upward or downward movement for independent applications of pressure at the upper and lower sides. In this system, it is the intent that the pressures for upper and lower stones be indi-

vidually controlled through the use of pressure control valves and indicating gauges in the pressure lines. In the system, as herein illustrated, a suitable pump 118, driven by motor 119, operates to draw a liquid pressure medium from a storage tank 120 through a pipe 118' and to deliver it through a pipe 120' to a safety relief valve 150 of a type whereby a desired maximum pressure may be set. A pipe 151 leads from valve 150 to a four-way valve 152 controlled by a valve lever 152a that is adjustable from a closed position P to positions P¹ and P². From the valve 152, pipes 153 and 154 are extended to deliver the pressure medium in accordance with the setting of the lever 152a to the upper and lower ends respectively of the jack cylinders 110 and to the lower ends of jack cylinders 100.

The pressure medium is supplied to the lower ends only of cylinders 100, and this is through a pipe 156 that leads from pipe 153 to a pressure reducing valve 157, from which valve a pipe 158' leads to supply the various jacks 100 with the medium at a pressure that is in accordance with the pressure setting of valve 157.

The pipe 153 likewise has a pressure regulating valve 157a interposed therein for control of pressures delivered to the jacks 110, and the valves 157 and 157a, respectively, have circulating connections 158x and 153x leading to the pipe 154. Also, in those pipe connections between pipe 154 and lower ends of the various jack cylinders 110, and in the pipe connections between the supply pipe 156' and lower ends of jacks 100, are flow restriction fittings 160. The cylinders 100 are equipped with drain connections at their upper ends into a pipe 156x which leads back to tank 120. This is to take care of any leakage past the jack pistons.

By use of the valves 157 and 157a, the pressure of the hydraulic medium at the outlet sides may be regulated and maintained within a wide range so long as the inlet pressure is somewhat above the outlet pressure. These valves will drain the system at the low pressure side as soon as the oil flow is stopped at the inlet side.

Assuming the pressure system to be as above described, it is understood that with relief valve 157 set at a desired maximum pressure, the control lever of valve 152 is adjusted to position P' and the pump started. The valve 152, in this setting, will direct the pressure medium through pipe 154 into the lower chambers of the upper jacks 110 and lift their pistons slowly on account of the flow restriction fittings 160. As soon as the suspension hooks 94 are relieved of their loads, and the hooks released, the valve lever 152a is shifted to position P² and the oil flow will now be divided into the two pipes 153 and 156. On passing through reducing valve 157a which has been set for the desired pressure, the pressure medium will enter the top chambers of jacks 110 and actuate their pistons downwardly, slowly on account of flow restriction fittings 160. By the pipe connection 154, the pressure medium from the lower chambers of jacks 110 will be led to valve 152, thence back to tank 120 through a pipe connection 158. In a like manner, the pressure medium from pipe connection 156 passes through the reducing valve 157, which has been set for a desired grinding pressure, into the lower chambers of the cylinders of jacks 100, starting the pistons slowly upward for their pressure strokes.

The prevailing grinding pressures can be observed by reference to the pressure gauges which have been shown as being connected with the reducing valves 157 and 157a.

When it is desired to shut down the system, the valve lever 152a is moved back to position P¹. The oil entering the lower chambers of jacks 110 will press their pistons upwardly, thereby displacing the oil from the upper chambers through pipe 153 and reducing valve 157a, and through the four way valve 152 into drain line 158 to storage. The weight of the bottom stone will force the medium from the lower chambers of jacks 100 through valve 157 and valve 152 to the drain 158. The pipe connections 153x and 156x make it possible to maintain a constant circulation through the reducing valves 157 and 157a, which is necessary in order that these valves, in operation, may maintain an even static pressure on the low pressure side of the valves and to take care of possible oil losses through piston leaks.

In the above system, for individual pressure applications, it will be understood that the gauge readings for top and bottom stones would not show the same because of the effect of the weights of the stones. Therefore, to make it possible for both gauges to read the same when like grinding pressures are being applied, it is necessary to provide specially calibrated dials for the two gauges which would take into consideration the influences of the weights of the stone. Thus to allow the mill operator to always set the gauge pressures alike for the top and bottom grinding surfaces, which would simplify the mill operation.

In Fig. 12 is illustrated in a diagrammatic way, a hydraulic pressure system for mills in which the center stone is of the floating type, as differentiated from being fixed. For this floating arrangement, single acting hydraulic jacks 100 are used to lift the bottom stone and to provide the desired grinding pressure. The pressure medium in this instance is supplied from tank 130 by pump 118, which delivers it through a relief and pressure adjusting valve 170 like valve 150 previously described, and from valve 170, it passes through pipe 172 and four-way valve 173 to pipe 174 whereby it is delivered to the various jacks. The valve 173 has a drain pipe connection 178 to the tank, and when the valve is adjusted for release of the pressure, the jacks drain their pressure medium, and the stones will separate by reason of their own weight. Pressure of the top stone is effected through the use of adjustable spring 175.

In this arrangement, the higher grinding pressure of the top stone due to its weight, may be counteracted by feeding more liquor to the lower stone.

Having thus described my invention, what I claim as new therein and desire to secure by Letters Patent is—

1. A mill of the character described comprising a series of three horizontal stones in face to face opposition for the grinding of material between them, means for feeding material between opposed grinding surfaces at opposite sides of the middle stone, means for supporting the middle stone at a fixed level for rotation, means for rotating the middle stone, means supporting the outer stones against rotation and for adjustment from and toward the middle stone, and hydraulically powered means for the adjustment of the upper and lower stones; said means comprising a hydraulic circuit, means operable to maintain flow of a hydraulic pressure medium therein at higher than grinding pressures, hydraulic jacks supporting the upper and lower stones, pressure applying connections between the hydraulic circuit and said jacks, a control valve incorporated in said connections and operable to effect the application

of pressure medium to the jacks to move the stones from or toward each other, and pressure relief valves in the connections between the jacks and control valve for determining the effective grinding pressures.

2. In a mill of the character described, a set of three horizontal stones in face to face opposition for the grinding of material between them, means supporting the middle stone at a fixed level, means mounting the upper and lower stones for adjustment toward and from the middle stone, means for causing relative rotation of the stones, means for feeding material between the stones for grinding, and a hydraulically powered means for adjusting the stones; said means comprising a plurality of hydraulic jacks for adjusting each of the adjustable stones, a hydraulic pressure circuit, means for maintaining a predetermined hydrostatic pressure therein, a control valve connected with the said pressure circuit, pressure lines from the said control valve to the pressure sides of the jacks, return connections from the lifting sides of the jacks to the control valve, pressure relief valves in the said pressure lines, relief connections from said pressure relief valves to the said control valve, and a return connection between the control valve and the pressure circuit; said control valve being operable to direct the pressure medium from the pressure circuit to either side of the jacks.

3. In a mill of the character described, a main frame structure, a set of horizontally disposed stones mounted therein for the grinding of material between them, means for the delivery of material between the stones for grinding, means for supporting the lower stone at a predetermined grinding level, means for causing relative rotation of the stones, means for lifting the top stone clear of the lower stone for shut-down periods, spring pressed hooks pivoted in the frame and adapted to be functionally engaged by the stone when it is lifted to shut-down position for the positive support thereof, and means common to all hooks to effect their simultaneous release from the stone.

4. A mill as recited in claim 3, wherein the said last mentioned means comprises a solenoid associated with each hook adapted, upon energization, to actuate the hook to disengaged position, a circuit for the solenoids and a switch in the circuit.

5. In a mill of the character described, a set of three horizontal stones in face to face opposition for the grinding of material between opposed surfaces, means for supporting the middle stone at a fixed level, means adjustably mounting the upper and lower stones for movement toward and from the middle stone, means for effecting relative rotation of the stones, means for feeding material between the stones for grinding, hydraulically powered means for positioning the upper and lower stones, including a plurality of hydraulic jacks for acting on each stone, a circuit of hydraulic pressure medium flowing at a constant maximum pressure, a control valve in the circuit, individual distributing circuits leading from the control valve respectively to supply the sets of jacks of upper and lower stones, pressure regulating valves in the distributing circuits whereby predetermined pressures may be maintained on the stones at opposite sides of the central stone, by-pass connections from the last named valves to the circuit.

LEONARD DOTZER.
